Patented May 23, 1922.

UNITED STATES PATENT OFFICE.

BRADFORD B. HOLMES, OF NEW YORK, N. Y.

ORDNANCE.

1,416,827.

Specification of Letters Patent. Patented May 23, 1922.

Application filed January 10, 1921. Serial No. 436,262.

To all whom it may concern:

Be it known that I, BRADFORD B. HOLMES, a citizen of the United States, and resident of New York city, in the county of New York and State of New York, have invented 5 certain new and useful Improvements in Ordnance, set forth in the annexed specification; and I do declare the following to be a full, clear, and exact description of the invention, such as will enable others skilled in the art to which it appertains to make and use the same.

This invention relates to ordnance.

Ordnance as usually constructed has many 15 detriments, some of which are as follows:

1. Relatively low velocity of projectile.
2. The utilization of only a small percentage of the energy in the powder.
3. Heavy recoil to be absorbed.
4. Excessive length of barrel in proportion to the diameter of the bore.
5. Rifling of barrel and short life.
6. Flash.
7. Noise.

25 The object of this invention is to ameliorate the first four of the above items and to eliminate the last three.

In firing a projectile from the barrel of a gun, it is customary to ignite a charge of 30 powder behind the projectile; the grains of the powder charge being so compounded and formed that combustion takes place practically uniformly, and the powder gas pressure is practically uniform during the travel 35 of projectile through the bore. It is apparent that at the time the projectile leaves the barrel, there is a large amount of energy remaining in the high pressure unexpanded gases in the barrel, and actually only some 40 10% of the energy in the powder is expended on the projectile.

The recoil of the gun is due to the reaction of the projectile and escaping gases against the breech, and the gases form a very 45 considerable portion of the recoil energy which must be absorbed.

In order to keep the projectile head-on in flight, it is customary to impart rotation to the projectile by rifling the barrel. The 50 imparting of rotation to the projectile absorbs some of the powder energy, and the rotating lands and grooves on the rifling rapidly wear away so that the life of a high velocity gun is short. It is probable that 55 the high powder pressures and temperatures play an important part in gun erosion. Heretofore, it has been impractical to at-

tain projectile velocities of much more than 3,000 ft. per sec. because of the high gas pressures and rapid erosion of rifling.

Again, when powder is burned as above described, a long gun is necessary to develop high velocity, and high velocity guns are usually 50 calibres or more in length.

The noise, flash and concussion of the muzzle blast are serious objections as they furnish means by which the location of guns can be detected as by sound, flash, or radiant heat ranging; as well as being a source of nervous fatigue to the gun crews.

Attempts have been made to increase the velocity of a projectile by using a smooth bore barrel and so shaping the projectile that its wind resistance would keep it head on in flight like an arrow. Such projectiles are usually made cigar shaped with fins or vanes at the rear, somewhat like a submarine torpedo in shape. Extremely high velocities and long range have thus been obtained but the dispersion of the projectiles has been bad because the muzzle blast escaping at the rear of the projectile and through the fins caused the projectile to be deflected erratically, so that, heretofore, this method of overcoming the use of rifling 85 has not been successful.

One of the main objects of this invention is to provide a means for launching a vaned projectile truly in its flight without the disturbing features of a muzzle blast to deflect it.

Generally stated, my invention consists of rigidly securing a vaned projectile to a cup shaped piston whose diameter is considerably greater than that of the projectile so that with a given powder pressure there will be a larger surface on which it acts with the consequent increase of acceleration imparted to the projectile; securing said piston or cup to the barrel of the gun by a retaining member in such a way that it will not become released and free to move until practically all the powder in the charge has been consumed with a resultant high gas pressure sufficient to shear the retaining member 10 whereupon the high gas pressures acting on a large piston surface relative to the mass of the projectile, generate terrific velocity in the projectile in a short length of barrel and at the same time cause rapid expansion 11 of the gases so that their pressure is greatly reduced at the time the projectile leaves the barrel; arresting said piston or cup near the muzzle without materially retarding the

projectile, and utilizing said cup or piston to keep the powder gases within the barrel of the gun so that flash, noise, disturbing effect on projectile and recoil due to powder blast are eliminated; providing means for the relatively noiseless and slow escape of the gas from the bore and automatic release of the piston or cup when said gases have almost entirely escaped.

By utilizing a large piston area relative to the mass of the projectile and holding the projectile and piston stationary until the full powder pressure is nearly attained, I am able to develop extremely high velocity in a short barrel—about 15 calibres—and at the same time utilize the majority of the energy of the powder in useful work, and accordingly the powder charge necessary to impart a given velocity to a given projectile can be less than when powder is burned in the usual way.

This principle also greatly reduces the recoil so that a simple recoil system is sufficient and in many cases no recoil system is necessary between the gun and carriage.

The short length of barrel materially aids construction, transportation and concealment and the gun is proof against discovery by heat, sound and flash ranging.

It can be made in all sizes from a pistol to a large naval gun in all cases where extreme rapidity of fire is not essential. In its present form, it would not be suitable for machine guns and a special adaptation of the invention for very rapid fire is made the subject of another patent application, Serial No. 438,099, filed January 18, 1921.

I am aware that projectiles have heretofore been equipped with cups or pistons and that means of arresting the cup have been used. My invention, however, differs from others of this type in that it combines with the cup the only kind of a projectile except a sphere which maintains a head-on flight without rotation, and, so far as I am aware, provides the only means yet devised by which such a projectile can be launched by the action of powder without disturbing forces tending to deflect the projectile from its true line of flight. Also, I provide for the automatic and timed expulsion of cup and gases which is an essential feature in this type of weapon which must be entirely served from the breech.

The above and other objects and features of the invention will be more fully described and explained in the following specifications and accompanying drawings, in which,

Fig. 1 is a longitudinal vertical cross section taken through the center of the gun before firing.

Fig. 2 is a longitudinal vertical cross section of the muzzle at the moment just prior to discharge of the cup after firing.

Fig. 3 is a front view of Fig. 1.

Fig. 4 is a front view of Fig. 2.

Fig. 5 is a rear view of one form of projectile.

Fig. 6 is a side view of the same.

Fig. 7 is a view of the front end of the gun showing in section a cup deflector.

The numeral 1 indicates a gun barrel closed at its rear end by the breech block 2 and breech block housing 3. The parts 2 and 3 may be of any conventional type, and 75 contain the usual cartridge ejector and firing mechanism, the firing pin 4 only of which is shown. The barrel 1 is provided with the smooth cylindrical bore 5, the enlarged chamber 6 for the reception of the 80 cartridge and a shoulder 7 formed between the bore and cartridge chamber. All the above elements are usual, the only point being that the breech block must be of such a design as to push the cartridge firmly up 85 against the shoulder 7.

The cartridge is made up of the following elements:

Projectile 8 fitted with vanes or fins 9 and attached to the cup shaped piston 10 by rivet 90 11. Rivet 11 is reduced in diameter at a point 12 so that it will break at that point and not pull the rivet head through the cup when the projectile leaves the cup. A cartridge case 13 surrounds the cup and the 95 open end of the case is spun or pressed at 14 around the shoulder of the cup, retaining the cup in place and forming a water tight joint. A percussion cap or primer 15 is inserted in the rear end of the cartridge and a hole 16 100 permits the flame from the cap to enter the powder chamber of the cartridge and ignite the powder 17 when the gun is fired.

It will be noted that when the cartridge is inserted as shown in the gun, that the cup 105 is retained in position by the shoulder 14 of the cartridge case and shoulder 7 of the barrel, and that the gas pressure must rise in the powder chamber to a point great enough to cause the cup to shear off the circular rim 110 or shoulder 14 before the cup and projectile start to move. The result of this action is that a very high initial pressure is built up in the powder chamber which is suddenly released, and acting on the large piston area, 115 develops extremely rapid acceleration in the projectile. The limit to this action is the point where the base of the projectile would crush or pierce the piston because of the inertia resistance of the projectile. 120

It will be seen that it is absolutely necessary that the projectile be held firmly against the cup so that cup and projectile move together as a unit. If there were the slightest distance separating the base of the 125 projectile and the cup, the cup would hit the projectile a blow instead of pushing it forward, and the device would not then function properly. The attachment of the projectile to the cup is therefore of the greatest 130

importance. Three methods of making this attachment suggest themselves, i. e., to screw, weld or rivet the cup to the projectile. The objection to screwing the two together is that the handling and bumping over the roads, etc., in ammunition wagons, would loosen a projectile from the cup now and then. Also, if the detachment of projectile and cup occurred by stripping the threads, eccentric strains might be applied to the projectile, the side having the fewest threads stripping first.

The objection to welding is that it is difficult to get a uniform attachment at a point and any eccentric strain on the base of the projectile at the moment of breaking contact with the cup would cause the projectile to deviate from its true line of flight.

Where the cup and projectile are attached by riveting an initial strain is set up in the rivet which holds the two parts tightly together, and by making the rivet slightly smaller as at 12, fracture will occur at that point, the resistance of which will be always axially applied to the projectile and will not cause it to deviate from its true line of flight. The head of the rivet remains in the cup sealing the rivet hole and preventing escape of gas.

This invention is a gun, and the first essential of a gun is that it shall launch its projectile on a line of flight coincident with the axis of the bore. The manner of attachment of projectile and cup is, therefore, of the greatest importance in that no deviating influence shall cause the projectile to be erratically launched, and the method of attachment here shown fulfills this requirement.

Near the muzzle of the gun are a plurality of conical segments 17 tapering forward from the full bore diameter to a circular opening 18 large enough to permit the passage of the projectile without touching. These segments have exterior conical surfaces 19 which contact with similar interior conical surfaces on a sleeve 20 which surrounds them and also surrounds the muzzle 21 of the barrel. The muzzle 21 is provided with a U packing 22 and packing retainer 23, and the sleeve 20 with a U packing 24 and packing retainer 25. The annular space 26 enclosed by packings 22 and 24, barrel muzzle 21 and sleeve 20 is filled with a liquid under pressure which urges sleeve 20 in the direction of the breech and thus forces the segments 17 into the position shown in Figs. 1 and 3, the inner surface of the segments thus forming a smooth cone.

Liquid under pressure is supplied to space 26 from an ordinary tank containing liquid and low pressure compressed air. This tank is not normally a part of the gun and can conveniently be mounted on the carriage so that it is not illustrated in the drawings.

A hose 27 runs from the tank to a spring pressed check valve 28 permitting liquid to flow freely from the tank and hose 27 into space 26 via hole 29. The valve seat has one or more notches 30 in it providing restricted communication from the space 26 to the hose 27 and tank. The compressed air acting on the liquid serves to force it into space 26 urging sleeve 20 towards the breech. When the cup 10 hits the conical surfaces of segments 17, it is substantially brought to rest by being deformed into the cone and without imparting much movement to the segments 17 or sleeve 20, owing to the weight and inertia of these parts and the resistance of the liquid in space 26 to sudden flow through the restricted orifices 30. The projectile breaks loose from the cup at 12 and passing through hole 18, continues on its line of flight.

The cup acts as a plug, the rearward thin edge being expanded by gas pressure into sealing contact with the barrel and prevents the escape of gas from the bore. A second important requirement is thus fulfilled, i. e., that no disturbing muzzle blast shall act on the base of the projectile to deflect it from its true line of flight after it leaves the muzzle.

The gas pressure in the bore acting against the cup or piston urges it forward which expands the segments 17 which force the sleeve 20 forward, which squeezes the liquid in 26 through the throttled orifices 30 into the hose 27 and the tank. The liquid in 26 and the orifice thus form a hydraulic brake which permits sleeve 20 to move slowly forward under the action of the gases in the bore.

Attached to packing retainer 25 is a valve stem 31 and valve 32 which controls a gas outlet hole 33. As the sleeve 20 moves forward it opens valve 32 permitting the gases in the bore to escape to the atmosphere via hole 33, pipe 34 and muffler or silencer 35. Any type of silencer suitable for the purpose may be used, its object being to permit the gas to escape relatively slowly, noiselessly and without flash. A few seconds are necessary for this and the throttling valve 30 and gas valve 32 must be so designed that sleeve 20 advances to the position shown in Fig. 2 and Fig. 4 allowing segments 17 to expand and permit the escape of cup 10 under a slight gas pressure before all the gas in the barrel has escaped. The cup leaves sleeve 20 and striking the deflector 36 (Fig. 7) falls to the ground. Deflector 36 is secured to sleeve 20, and its object is to prevent the cup from shooting forward after leaving the muzzle. The deflector has a hole 37 smaller than the cup 10 to permit the passage of the projectile.

The slopes of the inner and outer conical surfaces of segments 17 should bear such a

relation to each other that the pressure exerted by the cup will force the segments outwardly in a direction perpendicular to the axis of the bore rather than forward 5 with the sleeve 20.

Owing to the fact that the hot gases are retained for a short interval of time in the bore, the barrel 1 will absorb more heat than is usual when the gases escape immediately 10 with the projectile. Therefore a water jacket consisting of the tube 38 secured to breech housing 3 and a ring 39 screwed onto the barrel near the muzzle, provide a means of cooling the barrel. A plug 40 in ring 39 15 serves as an inlet for the water.

Details of the carriage, trunnions, liquid tank supplying space 26, and other usual accessories to a gun mount are not shown as they are in common use in ordnance.

20 To prevent escape of gas about valve stem 31, a copper cup packing 41 is secured between valve 32 and stem 31 which seals the sliding joint.

Figs. 5 and 6 show a slightly different 25 form of projectile base in which the fins are cut by slotting out of the base of the projectile.

The action of the gun is as follows:

The breech is opened and the cartridge inserted. The breech is closed shoving the cartridge firmly into its seat against shoulder 7. The primer 15 is fired which ignites the powder 17 and as soon as the gas pressure is sufficient to shear off the end 14 of 30 the cartridge case, the projectile and piston or cup 10 move rapidly up the bore.

Work is done on the projectile and cup by the expansion of the gas in 17 rather than by addition of fresh constant pressure gas as is now customary where the powder is burned slowly. The length of the barrel should be such that the gas expands to a point where further expansion of the gas will impart no additional acceleration to the projectile. Such a length will be less than the present usual length of 50 calibres, 15 to 20 calibres being nearer the proper figure, hence the length of the barrel is materially reduced. The cup guides the projectile truly through the bore, and the tapered rear edge under the expansion force of the gases forms a leakless joint between the cup and bore. The cup is essentially a piston, and is adopted because it offers an inexpensive and light construction, but obviously other types of piston may be substituted.

The cup is almost brought to rest in the muzzle cone and its energy is absorbed by deforming the cup. The projectile tears loose breaking the rivet 11 at 12 and passing through holes 18 and 37 continues truly on its line of flight with no deflecting forces ending to deflect it other than the action of gravity and wind to which all projectiles are subject.

On firing the gun, recoil energy is transmitted to the breech block from the reaction of the powder gases, the cup and the projectile. The cup and gases being arrested in the muzzle cone, the only unbalanced recoil reaction is that of the projectile, and as the mass of the gun is large in proportion to the projectile, in many cases the recoil is so slight that no recoil check will be necessary between the gun and carriage.

70 The gas pressure acting on the piston pushes sleeve 20 forward, opening gas outlet 33 which permits the gas to escape under control and finally the cup to be ejected as has been described. After the escape of the 80 cup, the liquid pressure in 26 brings the segments 17 and sleeve 20 back to the firing position shown in Fig. 1.

75 It is apparent that this invention permits

1. The attainment of very high velocity of 85 projectile with

2. The utilization of a relatively small powder charge and

3. A light recoil and with

4. Short barrel length.

90 5. Also, that it permits the firing of a projectile designed to maintain a head-on flight due to its conformation and reaction with air resistance without any disturbing influence acting on it at the moment of discharge which would tend to deflect it from its true line of flight.

95 6. That such a projectile may be very long and tapered at both ends to give minimum air resistance and consequently long range 100 for a given mass and velocity.

7. That rifling and consequent bore erosion are eliminated, and

8. Due to the retention and controlled escape of gases from the bore, no flash and

105 9. Relatively no noise accompanies the discharge.

It is apparent that there are many other ways in which this invention may be realized, and I contemplate its use in other relations, so I do not restrict myself to the form of the preferred embodiment herein illustrated, except as defined in the claims.

I claim

1. In a device of the class described, a 115 projectile, a cartridge case, a piston within said cartridge case adapted to impart motion to said projectile, and means normally retaining said piston within said cartridge case.

120 2. In a device of the class described, a projectile, a cartridge case, an explosive charge within said case, means for igniting said explosive charge, a piston within said case and adapted to impart motion to said projectile, means for retaining said piston in said case until high gas pressures have been developed by the ignition of said explosive charge.

125 3. In a device of the class described, a 130

- barrel, a projectile, a cartridge case, a piston within said cartridge case adapted to impart motion to said projectile, an explosive charge within said cartridge case, means for igniting said explosive charge, and means for retaining said piston in said case until the development of high gas pressure due to the ignition of said explosive charge, said means comprising a shearing member interposed between said piston and barrel and adapted to shear under heavy pressure.
4. In a device of the class described, a vaned projectile, a cup shaped piston and means for securing said projectile and piston together, said means comprising a rivet with a reduced diameter at a given place.
5. In a device of the class described, a cartridge case, a cup shaped piston within said cartridge case, an explosive charge within said case and said piston, means for igniting said explosive charge, a vaned projectile attached to said piston, and means comprising the walls of said cartridge case overlapping the forward end of said piston for retaining said piston within said cartridge case until rise of pressure due to ignition of the explosive charge is sufficient to cause shearing of said retaining means.
6. In a device of the class described, in combination, a barrel; a projectile; an explosive charge; a piston adapted to impart motion to said projectile upon ignition of said explosive charge, said piston being materially greater in diameter than said projectile; and means allowing the passage of said projectile from said barrel but adapted to retard the motion of said piston and retain it in said barrel for a period of time and thereafter allow its discharge.
7. In a device of the class described, in combination, a barrel; a projectile; an explosive charge; a piston adapted to impart motion to said projectile upon ignition of said explosive charge, said piston being materially greater in diameter than said projectile; and means allowing the passage of said projectile from said barrel but adapted to retard the motion of said piston and retain it in said barrel for a period of time and thereafter allow its discharge, said means comprising conical segments adapted to expand under the pressure exerted by said piston.
8. In a device of the class described, in combination, a barrel; a projectile; an explosive charge; a piston adapted to impart motion to said projectile upon ignition of said explosive charge, said piston being materially greater in diameter than said projectile; and means allowing the passage of said projectile from said barrel but adapted to retard the motion of said piston and retain it in said barrel for a period of time and thereafter allow its discharge, said means comprising conical segments controlled by an hydraulic brake and adapted to slowly expand under the pressure exerted by said piston.
9. In the combination of claim 6 the additional feature of a deflector to deflect the line of flight of the piston from the line of flight of the projectile after the piston has been expelled from the barrel.
10. In a device of the class described, a barrel; an explosive charge; a projectile; a piston adapted to impart motion to said projectile under action of said explosive charge and arranged to prevent the escape of gas from said barrel; a restricted orifice near the muzzle permitting the unrestricted passage of said projectile but retarding the motion of said piston near the muzzle end of said barrel; and means for controlling the escape of gases generated by the explosive charge from the barrel, during the time of retardation of said piston in said barrel muzzle.
11. In a device of the class described, in combination, a barrel member; a powder charge; a projectile; a piston adapted to impart motion to said projectile under action of the gases from the ignition of said powder charge and to seal said gases in said barrel; means permitting the unrestricted passage of said projectile from said barrel but retarding the motion of said piston near the muzzle, and a valve operated by said piston retarding means permitting and controlling the escape of said powder gases during the time of retardation of said piston in said muzzle.
12. In the combination of claim 11 the added feature of a silencer to silence the discharge of said gases.
13. In a device of the class described in combination; a barrel; a powder charge in said barrel; a projectile; a piston set in motion by the expansive force of gases generated from the burning of said powder charge and adapted to impart motion to said projectile and seal said gases in said barrel; conical segments adapted to retard the motion of said piston near the muzzle of said barrel, said segments being retained by a sleeve and a hydraulic brake adapted to permit the slow and controlled expansion of said conical segments under the thrust of said piston, and to permit the expulsion of said piston after an interval of time, and a gas outlet operated and controlled by the motion of said sleeve to permit the escape of gases from said barrel during the time of retardation of said piston by said conical segments.
- Signed at New York city, in the county of New York and State of New York, this 8th day of January, A. D. 1921.
